ATTORNEYS

UNITED STATES PATENT OFFICE

ISADORE MINK, OF BROOKLYN, NEW YORK

DESIGN FOR A DIAPER

Application filed October 31, 1930. Serial No. 37,466. Term of patent 7 years.

To all whom it may concern:

Be it known that I, ISADORE MINK, a citizen of the United States, and a resident of New York city, borough of Brooklyn, in the county of Kings and State of New York, have invented the new, original, and ornamental Design for Diaper, of which the following is a specification.

Reference is had to the accompanying drawings, forming part thereof, wherein—

I claim—

The ornamental design for a diaper substantially as shown and described.

ISADORE MINK.
